Primary Examiner — George D. Kirschbaum*Assistant Examiner* — Maria J Edwards(74) *Attorney, Agent, or Firm* — Sterne, Kessler, Goldstein & Fox P.L.L.C.(57) **CLAIM**

The ornamental design for a goggle, as shown and described.

DESCRIPTION

FIG. 1 is a front perspective view of a goggle showing the claimed design;

FIG. 2 is a top front perspective view thereof;

FIG. 3 is a front view thereof;

FIG. 4 is a rear view thereof;

FIG. 5 is a right side view thereof, the left side view being a mirror image thereof;

FIG. 6 is a top view thereof; and,

FIG. 7 is a bottom view thereof.

The dashed broken lines in the figures show portions of the goggle that form no part of the claimed design.

The dot-dash broken lines in the figures show boundaries of the claim and form no part of the claimed design.

1 Claim, 4 Drawing Sheets(56)
